C. J. MANVILLE

ILLUMINATED HOUSE NUMBER

Filed Sept. 17, 1920

WITNESS:

INVENTOR:

R. F. Buckley.
R. H. Sample.

UNITED STATES PATENT OFFICE.

CHARLES J. MANVILLE, OF INDIANAPOLIS, INDIANA.

ILLUMINATED HOUSE NUMBER.

Application filed September 17, 1920. Serial No. 410,915.

To all whom it may concern:

Be it known that I, CHARLES J. MANVILLE, a citizen of the United States, residing at Indianapolis, in the county of Marion and 5 State of Indiana, have invented a new and useful Illuminated House Number, of which the following is a specification, reference being had to the accompanying drawings and to the letters and figures of reference marked 10 thereon.

This invention relates to means for holding and illuminating house or building numbers, and has reference more particularly to incandescent lamp arrangement for providing 15 light for illuminating the numbers.

An object of the invention is to illuminate house or building numbers to such an extent that they may be legible from a measurably distant sidewalk or street at night time.

20 Another object is to provide changeable yet simple and inexpensive illuminated house numbers in order to eliminate the disturbing of the occupants of near-by houses when a stranger is looking for a certain 25 house number after darkness of night occurs.

A further object is to provide house numbers that may readily be illuminated, thereby enabling people who may be searching for 30 a house number to approximately locate the place being searched for which may not be illuminated, through the advantage of a near-by house having illuminated numbers.

A still further object of the invention is to cause the numbers on a house to stand out 35 clearly at night when dark shadows are thrown on the house from various lights, even though the streets have street lights.

Referring to the drawings,—Figure 1 is 40 an elevation of the illuminated number provided in fulfillment of the above-mentioned and other objects, as preferably constructed, a portion of the lamp housing being shown in section; Fig. 2 is a fragmentary section 45 on the line II—II on Fig. 1; Fig. 3 is a transverse section on an enlarged scale on the line III—III on Fig. 1; Fig. 4 is a fragmentary side view of a spring appearing as used in Fig. 3; Fig. 5 is an elevation of the 50 illuminated number in a slightly modified form, a portion being in section.

Similar reference characters in the different figures of the drawing indicate like parts or features of construction herein referred to.

55 In a practical embodiment of the invention a novel frame or casing is provided to

hold a house or building number and a lamp to illuminate the number without exposing the observer to the glare of the light. The frame or casing constituting the number holder comprises preferably a back or base plate 1 which preferably is composed of sheet metal, an approximately hollow cylindrical lamp house shell 2, the wall of which extends upwardly and forwardly from the base plate and downwardly and towards but not to the base plate, and from the end of which extends a front frame opposite to and parallel with the base plate, the front frame comprising a horizontal upper member 3 adjacent to the shell, two vertical side members 4 and 5 extending from the upper member, and a horizontal lower member 6 connected with the side members. Thus a clear opening 7 is provided through which light may 70 pass from the interior of the housing shell to the space between the back plate and the front frame. The base or back plate has a narrow bottom plate 8 thereon, preferably integral therewith and the bottom plate 80 preferably has a narrow front clip plate 9 thereon arranged opposite to the base plate.

The device constituting the house or building number may be variously made and of any suitable material to permit light to pass 85 through the front plate which is secured on the front frame and bears the number. Preferably a thin sheet 10 of suitable transparent or semi-transparent material, such as celluloid, is made separately and placed on the front of the front frame, and the number plate is composed of a suitable number of number plate sections 11, 12, 13 arranged on the front of the sheet, the sections having 90 suitable numerals, as 14, 15, 16 respectively cut from the material to permit light to pass through the sections; but obviously the numerals may be otherwise rendered transparent or semi-transparent. The holder has an end wall constituting a closure cap 17 having clip flanges 18 and 19 that embrace the number plate and the base plate respectively and a flange 20 on its lower end that embraces the bottom portion 8; and the end wall has also an approximately circular cap portion 21 which has a cylindrical flange 22 that embraces the cylindrical shell 2. The opposite end of the holder is similarly provided with an end wall or closure plate 23 having flanges 24 and 25 embracing the number plate and the base plate respectively, a bottom flange 20', and a cap plate 26 having

105

110

115

- a cylindrical flange 27 embracing the cylindrical shell. The lower horizontal member 6 of the front frame is adjacent to the bottom plate 8, and a suitable serpentine spring 5 28, composed of a strip of thin elastic metal, is arranged between the base 1 and the member 6 to hold the number plate firmly against the clip member 9.
- A suitable electric lamp is suitably supported in the cylindrical lamp house or casing portion, and for such purposes a corrugated spring ring 29 is provided and arranged in the cylindrical casing adjacent to one end thereof, the cap plate 21 is provided 10 with an aperture 30, and a lamp holder or socket 31 is inserted through the aperture and into the spring ring and supports an incandescent electric lamp 32 which is supplied with current by means of a circuit wire 15 33 connected with a suitable battery 34 which may be a central power station, any suitable portion of the circuit wire being provided with a switch 35, the lamp having a grounding circuit 36.
- In a slightly modified form of structure 25 which is suitable for use when current from a central electrical power plant is not available, the portion of the casing that holds the number plate is provided with end walls 30 or caps 37 and 38 similar to those above-described excepting that they terminate adjacent to the cylindrical lamp casing or house, the latter having separate caps 39 and 40 on its ends respectively. The lamp 35 house shell has the spring ring 29 therein adjacent to one of its ends and preferably a similar ring 29' adjacent to the opposite end; and for furnishing the required light a dry battery cell 41 is arranged in the 40 spring ring 29 and is suitably provided on its inner end with an incandescent electrical lamp 42, and another battery cell 43 may be arranged in the other spring ring and provided with a lamp 44.
- The device is to be placed with the base 45 plate 1 against the wall of a building so that the lamp house shall be uppermost, the base plate having suitable holes 45 therein to receive screws or fastening devices with 50 the heads of the devices within the holder chamber, whereby the number holder may be secured in place. The interior of the chambers in the holder may be suitably finished for reflecting light.
- In practical use the current may be 55 switched on to supply the lamp on the approach of darkness, or at any time when desired to permit the house number to be plainly seen in the darkness of night. The 60 light from the lamp is reflected by the wall of the lamp house and diffused downward into the space behind the number plate, so that all the numerals or portions of the number are uniformly illuminated by diffused 65 light sufficiently to be plainly visible. At-

mospheric air may enter through the aperture 30 and the corrugations of the spring ring, while heated air may similarly escape from the upper portion of the lamp house. When the illuminated number is not desired 70 the current may be switched off.

Having thus described the invention, what is claimed as new is:

1. A house number comprising a holder with individually changeable numerals to 75 indicate relative positions of different houses, the holder including a non-variable base member to be vertically supported permanently on a house wall and a flat bottom plate extending horizontally from the base 80 member, the numerals being transparent on separate plates respectively, a number plate frame bodily supported vertically upon the bottom plate at a right angle thereto and bodily supporting the changeable numeral plates in vertical parallelism relatively to 85 said base member, two holder ends connected to said base member and loosely engaging the ends of the number plate frame and having separate portions engaging adjacent 90 portions respectively of the front of the frame, with a holder cover connected with said base member and ends and also connected at its lowermost portion with the top of said frame, a lamp socket in the holder, and 95 means to directly secure said base member permanently to a house.

2. In an illuminated house number, the combination with a holder box having a front plate bearing a transparent number, 100 the top of the box being open, of a lamp house comprising a cylindrical wall having an opening therein coinciding with the open top of the holder box, the ends of the wall having caps thereon, a corrugated spring-ring engaging the interior of said wall, and an electrical lamp supported in said house by means of said spring-ring. 105

3. In an illuminated house number, the combination of a number plate holder comprising a back and ends and also a bottom and a front frame, the bottom having a lip outside the end of the front frame, a transparent sheet on the front frame, number plate sections on the transparent sheet and extending under said lip, each section having an opening representing a figure therein, and a spring between said back and a portion of said front frame, with a lamp house connected to said back and said front frame, and an electrical lamp supported in the lamp house. 115

4. In an illuminated house number, the combination of a base plate, a bottom plate extending angularly from one end of the base plate, a clip plate extending from the end of the bottom plate opposite to the base plate, a lamp house wall extending from the opposite end of the base plate and being curved and extending forwardly and down- 120 125 130

wardly and terminating at a point distant from the base plate, an open front frame extending from the terminal of the lamp house wall to said bottom plate and behind said 5 clip plate, a transparent sheet on the front of said front frame, a plurality of number plate sections on said sheet and extending behind said clip plate, each of said sections having an aperture therein representing a 10 number character, a spring seated on the base plate and engaging a portion of said front frame behind said clip plate, a pair of end walls having flanges embracing opposite ends respectively of the base plate 15 and also flanges embracing portions of said sections, the end walls having cap plates thereon having flanges embracing opposite ends respectively of the lamp house wall, one of the cap plates having an aperture 20 therein, a corrugated spring-ring embraced by said lamp house wall adjacent to said apertured cap plate, a lamp socket supported in said spring-ring, and a lamp supported by said socket.

In testimony whereof, I affix my signature in presence of two witnesses.

CHARLES J. MANVILLE.
